UNITED STATES PATENT OFFICE.

CHARLES H. DÉS LAURIES, OF WEYMOUTH, MASSACHUSETTS, ASSIGNOR TO
EMERSON W. TORREY AND FRANK H. TORREY, BOTH OF SAME PLACE.

SHOE.

SPECIFICATION forming part of Letters Patent No. 425,598, dated April 15, 1890.

Application filed January 27, 1890. Serial No. 338,260. (No model.)

To all whom it may concern:

Be it known that I, CHARLES H. DÉS LAURIES, of Weymouth, county of Norfolk, State of Massachusetts, have invented an Improvement 5 in Shoe, of which the following description, in connection with the accompanying drawings, is a specification, like letters on the drawings representing like parts.

My invention relates to shoes of that class 10 in which a cork sole or equivalent filling-sole is employed between the insole and outsole. In shoes of this class there is a welt just below the upper, commonly called the "cork-sole welt," which is covered with a casing or strip 15 of thin leather, folded over and so as to wholly incase the said welt, and below this cork-sole welt there is a welt to which the outer sole is attached by sewing in the usual manner. In shoes of this class as heretofore made the 20 cork-sole welt and its inclosing strip or casing is attached to the inner sole of the shoe in the usual manner, the said cork-sole welt, with its casing, projecting beyond the level of the face of the inner sole and forming a ledge 25 around it, within which the cork sole is placed. Then a second inner sole is applied over the cork sole and cork-sole welt, and the main welt, to which the outer sole of the shoe is attached, is connected to the second inner 30 sole by stitches which pass through a channel in said second inner sole, through the edges of the upper and of the casing for the cork-sole welt, and through the outer welt of the shoe to which the outer sole is attached.

The object of the present invention is to 35 produce a shoe having a cork sole interposed between the inner and outer soles and having the same general appearance as shoes of this class heretofore made—that is, having an 40 incased cork-sole welt lying between the upper and main welt and raising the upper with its insole above the main welt a sufficient height to receive the cork sole between the inner and outer soles, the object being to 45 make said shoe of simpler construction and at less cost than those heretofore made. To accomplish this result in accordance with this invention, the inner sole of the shoe is provided with two channels, one being deeper 50 and extending nearer the edge or periphery

of the shoe than the other, and being called the "outer" channel to distinguish it from the other, which will be called the "inner" channel.

In making a shoe in accordance with this invention the upper is lasted over the insole 55 in the usual manner and the cork-sole welt and its casing are applied thereto, the said casing being unfolded and having one edge between the outer face of the upper and the cork-sole welt. These parts are then united 60 by stitches passing through the outer channel of the insole, the upper, one edge of the casing, and the cork-sole welt. Then the casing is folded or lasted over the cork-sole welt so as to inclose the same, and the welt 65 proper of the shoe is applied to said folded casing and is fastened to the insole by stitches which pass through the inner channel of the insole, the edge of the upper, the cork-sole welt, and both edges of its casing and the 70 outer or main welt, which latter is thus attached to the insole of the shoe, but held at a distance from the face of the insole equal to the thickness of the incased cork-sole welt, making a space between the outer face of the 75 insole and the level of the main welt to receive the cork sole, which is applied in said space, after which the outsole is attached to the welt in the usual manner.

Figure 1 is a transverse section of a lasted 80 shoe having a cork sole attached to the insole in accordance with this invention, the casing and the cork-sole welt being shown at one side of the shoe as folded or lasted over ready to receive the outer or main welt of the shoe. 85 Fig. 2 is a similar section showing the shoe with the main welt applied and attached to the insole after the latter has had the cork-sole welt applied thereto, as shown in Fig. 1; and Fig. 3, a similar section of the finished 90 shoe.

The insole *a* is applied to the last *b* and the edges of the upper *c* are stretched or lasted over the said insole in the usual manner, the said insole being provided with a channel *a*², 95 herein called the "outer" channel, which receives the seam or line of stitches *d*, by which the upper is connected to the insole in the usual manner of making sewed shoes.

Before uniting the upper and insole by the 100

seam *d* the cork-sole welt *e* and its casing *f* are applied over the edge of the insole, the said casing being unfolded, as shown at the right in Fig. 1, so that one edge of the casing 5 lies between the upper and the welt *e*, and the seam *d* passes through the insole, upper, one side of the casing *f*, and the welt *e*, as shown at the right hand of Fig. 1. The insole is, in accordance with this invention, provided with 10 a second channel *a*³, herein called the "inner" channel, as it does not extend so far toward the extreme outer edge of the insole as the channel *a*³.

After the cork-sole channel and its casing 15 have been attached to the upper and insole by the seam *d*, as shown at the right hand, Fig. 1, the casing *f* is lasted or folded over the welt *e*, as shown at the left-hand side of Fig. 1, after which the main welt *g* (see Fig. 2) is applied, resting upon the outer fold of 20 the casing of the cork-sole welt, and the said outer fold of the said casing and the main welt *g* are then united to the upper and insole by a seam or line of stitching *h*, (see Fig. 2,) which passes through the inner channel *a*³, 25 the upper, both folds of the casing *f*, and the main welt *g*, which is thus securely attached to the insole and upper in substantially the usual manner, but is separated from the upper by a space equal to the thickness of the cork-sole welt and its casing, thus leaving a 30 space between the level of the welt *g* and the outer face of the insole *a* sufficient to receive the cork sole *i*, which is applied in the said 35 space, as shown in Fig. 2.

In order to complete the shoe, the outsole *k*, (see Fig. 3,) one or more layers, as desired, 40 is sewed to the welt *g* in the usual manner, the completed shoe thus having the cork sole *i* interposed between the insole and outsole, and also having the incased cork-sole welt *e* appear between the edges of the upper and the

main welt *g*, as is usual in shoes having a cork sole outside the insole. The shoe does not, however, have a second insole, such as is 45 usually applied outside the cork sole and cork-sole welt and to which the main welt is commonly attached; but the main welt is attached to the single insole by means of the second channel with which said insole is provided, thus forming a shoe of simpler and less expensive construction, and at the same time stronger and more durable than shoes of usual construction having a cork sole between the insole and outsole. 50

I claim—

1. A shoe having an insole provided with two channels and an upper and cork-sole welt attached to said insole by a seam made in one of said channels, and a main welt attached to said insole and upper by a second seam in the second channel of said insole, substantially as and for the purpose described. 60

2. In a shoe, an insole provided with inner and outer channels, the upper lasted over the said insole, a cork-sole welt, and a casing therefor, one edge of which casing is interposed between the cork-sole welt and upper, the said parts being united by a seam in the outer channel of said insole, and a main welt applied over the outer fold of said casing, 70 which is folded or lasted over the cork-sole welt and united to the insole by stitches extending from the inner channel through the upper, both edges of the casing, and said main welt, substantially as and for the purpose described. 75

In testimony whereof I have signed my name to this specification in the presence of two subscribing witnesses.

CHARLES H. DÉS LAURIES.
